7 Claims. (Cl. 179—18)

This invention relates to telephone systems and more particularly to systems employing plunger type line switches.

The object of this invention is to improve the operation of plunger type line switches and to render their operation more reliable by eliminating the possibility of double connections.

The construction, operation and utility of plunger type line switches are too well known to require a detailed description here. It is also well known that systems employing these switches are subject to trouble from double connections caused by two or more switches being operated simultaneously. Such a seizure of one trunk by more than one line switch occurs when a plurality of calls are simultaneously initiated on lines associated with the same master switch. Since the battery is disconnected from the pull down windings of the magnets of all line switches of a group during the time that the shaft of the master switch is in motion, the line switches are prevented from operating to extend calls which have originated while the master switch is operating, with the result that double connections may also occur in case two or more calls are waiting when the operation of the master switch ceases and battery is again connected to the pull down windings of the magnets of the associated line switches.

The present invention provides an arrangement for controlling the battery connection for a group of plunger type line switches, in which a relay bridge is connected across two normally balanced current paths, the simultaneous initiation of a plurality of calls in one line group being effective to operate the relay due to an unbalance thereby created between the two paths. The operation of the relay increases the resistance in the battery connection sufficiently to prevent the complete operation of any of the line switches. The current is sufficient, however, to operate the bridge cut-off armature of the switches in question and thereby cause release of the associated line relays. When all but a single line relay has released, the balance between the two current paths is restored, thereby causing the release of the bridge relay and the consequent closure of the battery connection to cause the complete operation of the associated line switch.

The invention further provides an arrangement in which the ground connection for operating a group of line switches is controlled by a relay common to the switches and by chain contacts on a relay for each of the switches, the common relay being operated when two or more switches are seized simultaneously to prevent seizure of the same trunk by two or more of the switches.

The invention will be explained by reference to the accompanying drawings, in which Fig. 1 and Fig. 2 taken together, and with Fig. 1 at the left

of Fig. 2, show one of the forms in which the invention may be practiced.

The organization illustrated in the drawings, comprises as much of a complete telephone system as is necessary for a clear understanding of the manner in which the invention is organized and operates. There are shown in the drawings two calling lines extending from stations A and A₁ to a central office, one called line extending from the central office to station B, and connecting circuits at the central office, by means of which the telephone lines may be joined for conversation. The connecting circuits include individual line switches PLS—1 and PLS—75, secondary line switches SLS—1 and SLS—25 together with their master switches PMS and SMS all of which may be of the type described in Patent No. 1,586,530, granted June 1, 1926 to J. H. Homrighous. The connecting circuits further include a selector D and connector E which may be of the type shown in Patent No. 1,379,068 granted May 24, 1921 to J. Wicks. The particular parts of this system to which the invention is directed are shown at C and C₁.

Having given a general description of the apparatus involved in the system, the invention will be most readily understood from a detailed description of the operations involved in setting up a connection.

Upon the removal of the receiver at the calling station A preparatory to making a call, relay 101 of the primary line switch PLS—1 is operated over the calling line circuit. Relay 101 in attracting its armature closes a circuit including the pulldown winding 102 of the primary line switch PLS—1 which causes the line switch to seize the preselected trunk by operating the set of springs 138 in the well known manner, as shown and particularly described in above mentioned Patent No. 1,586,530 to Homrighous. The circuit for energizing winding 102 is traced from battery through the back contact of battery control relay 104, conductor 125, back contact of relay 106, through resistances 107 and 108 in parallel, back contact and winding of relay 105, over conductor 115, winding 102 of switch PLS—1, front contact of relay 101, conductor 140, through the low resistance left winding of relay 126 to ground. Relay 105 is operated by the current in this circuit to complete a Wheatstone bridge as hereinafter described. In addition to extending the calling line over conductors 111 and 112 to the secondary line switch SLS—1, a circuit for operating the secondary line switch is closed from ground at contact 121 of springs 138, thence over conductor 113, through resistance 222 at C₁ in Fig. 2, winding of relay 204, conductor 213, through pull-down winding 202 and normally closed contact of secondary line switch SLS—1, through the

winding of relay 201, conductor 214, left-hand armature and front contact of relay 207, contact on relay 210, thence over conductor 215, right back contact relay 212, conductor 216 to battery 5 through the left winding of relay 211. The pull-down winding 202 in the path just traced does not receive sufficient current at this time to operate line switch plunger 241 due to the resistance 222 which according to this invention has been inserted for preventing double connections. Relay 10, 201, however, operates to establish at its front contact a temporary holding circuit for the PLS-1 switch traced from battery through winding 103, contact 122 of springs 138, conductor 15 114, contact of relay 201, conductor 213, winding of relay 204, resistance 222, over conductor 113 to ground at contact 121 of springs 138.

The circuit for operating the secondary line switch SLS-1 is dependent on the operation of 20 relay 204 of the apparatus at C1 as will hereinafter be explained. Assuming for the present that pull-down winding 202 operates plunger 241 to extend the calling line to selector D, contact 239 opens the circuit through the winding of relay 25 201 which after an interval releases and removes that portion of the holding circuit for winding 103 of switch PLS-1 traced from the armature of relay 201 over conductor 213 to ground at contact 121 of switch PLS-1. Line switch PLS-1 30 does not however release because in the meantime the operation of plunger 241 of secondary switch SLS-1 closes contacts 240 and extends the holding circuit for winding 103 of switch PLS-1 to conductor 219 of selector D. Ground is now re- 35 turned over conductor 219, before relay 201 releases by selector D in the well known manner. When therefore the subscriber dials the wanted number, the selector D and connector E function to extend the calling line to the called subscriber 40 B in the usual manner described in above mentioned Patent No. 1,379,068 to Wicks. The holding circuit for winding 103 of the primary line switch PLS-1 is now extended to the connector E and remains under control of the calling subscriber. The holding circuit for the secondary line switch SLS-1 includes windings 203 and 45 202, contact 220, conductor 213, winding of relay 204, resistance 222, conductor 113 to ground at contact 121 of primary line switch PLS-1.

50 Referring now to the operation of the primary line switch PLS-1 it will be seen that battery for energizing the pull-down windings 102 of all primary line switches associated with the primary master switch PMS, which in previous systems of this kind it has been customary to supply directly from the master switch, is according to this invention supplied over conductor 115 from the master switch PMS under control of relays 105 and 106 at C. Operation of the primary master switch PMS does not differ essentially from the usual manner of operating such switches but the following description will however aid in obtaining a clearer understanding of the arrangement for preventing double connections at primary line switches.

55 The operation of primary line switch plunger 141 closes contact 121 of springs 138 and connects ground over conductor 118 to master switch bank contact 123, corresponding to the preselected 60 trunk, thence through master switch wiper 134 and the winding of relay 127 to battery. Relay 127 operating, closes a circuit from ground through the low resistance left-hand winding of relay 126, through the front contact of relay 127, conductor 119 and winding of relay 128 to bat-

tery. Relay 128 operates and at contact 124 closes a circuit from battery over conductor 120, through the winding of relay 104, and through the low resistance left hand winding of relay 126 to ground. Relay 104 operates and opens the 5 main battery supply over conductor 125 to the pull-down windings of all switches associated with this particular primary master switch. Line switch PLS-1 does not release, however, because of having established a holding circuit for itself 10 over lead 114 as previously described. In the circuit traced above for opening the battery feed to all line switches of a group it should be observed that the operation of relay 128 also disengages the locking arm 135 of the primary master switch PMS allowing the master switch spring 137 to move the line switch shaft 116 together with its idle line switches and master switch wiper 134 to the next idle trunk in the usual well known manner. The master switch 20 passes over trunks that are busy since the master switch bank contacts of busy trunks will be grounded from the line switch engaged therewith over a circuit similar to the one described above for operating relay 127 when switch PLS-1 25 operated. The master switch stops on an idle trunk due to the absence of ground on the master switch bank contact. Relays 127 and 128 then release in turn to permit the locking arm 135 to reengage the locking segment 136. Relay 128 releasing also releases relay 104 which again connects battery to feed conductor 125.

The aforementioned operation of relay 105, (due to the operation of line relay 101), completes a Wheatstone bridge comprising resistance 35 107 as one branch, resistance 108 equal to resistance 107 as another branch, and resistance 109 as a third branch. The fourth branch of the bridge includes the winding of relay 105, conductor 115 and the pull-down winding 102 of switch PLS-1 in parallel with the pull-down winding of any other switch the line relay of which is operated simultaneously with relay 101 of switch PLS-1. Resistance 109 is approximately equal to the sum of the resistances of the winding of relay 105 and the pull-down winding 102 so that there is not a sufficiently large difference in potential between the ends of the winding of bridge relay 106 to cause its operation, if line relay 101 of switch PLS-1 is the only line relay then operated. If, however, there are one or more additional line relays then operated, the resistance of the fourth branch of the bridge (which includes the winding of relay 105) 40 will be low enough to unbalance the bridge and a sufficiently large potential difference will then exist across the winding of relay 106 to cause its operation. If relay 106 operates due to the unbalanced condition created by the simultaneous operation of a plurality of line relays in the one master switch group, resistance 110 is inserted in series with conductor 125 so that the current through the windings of the pull-down windings of the switches in question is insufficient 45 to operate the plungers 141 of these switches but is sufficient to operate the bridge cut-off armatures to cause the release of the operated line relay 101 and the release of relay 105. The release of each of these line relays opens the circuit through the associated pull-down winding 50 and the release of relay 105 destroys the bridge and causes the release of relay 106.

55 Line relay 101 and relays 105 and 106 again operate and again restore to normal as just described and would continue in this way to pre- 60

vent the calling lines from being connected to the same trunk. It is well known that the time characteristics for the operation and release of such circuits differ among themselves to such an extent that after one or several operations they get out of step. Assuming then for example that relay 101 remains operated after the other line relays have released, the balance of the bridge is restored causing relay 106 to be deenergized. The resistance 110 is thus shunted out to cause the primary line switch plunger 141 to be operated and connect the calling subscriber A to the idle trunk. Another calling subscriber such as A1 is prevented from seizing the same trunk even if the associated line relay operates immediately following the operation of plunger 141 of switch PLS-1 because the connection of another pull-down winding in parallel with the pull-down winding of switch PLS-1 causes the reoperation of relay 106 to introduce resistance 110 in the battery supply circuit. Plunger 141 of switch PLS-1 that has already operated continues to hold, in spite of the increased resistance in the battery supply circuit, but the pull-down winding of the other switch does not receive sufficient current to operate its plunger. Thus it will be seen that the added apparatus at C effectively prevents more than one primary line switch from operating at a time.

It will also be understood that the above described circuit arrangement is equally effective in preventing double connections when a plurality of subscribers call simultaneously or when a number of switches attempt to seize an idle trunk after being held up on account of removal of battery from the pull-down windings by the master switch in its search for an idle trunk. Furthermore, it will be evident that this same circuit arrangement is similarly effective in those cases where secondary line switches are not installed and the trunks lead directly to selectors.

A description will now be given of the circuit arrangement by which double connections at secondary line switches are prevented. It is of course understood that every trunk from a primary line switch to a secondary line switch is equipped with a resistance and relay such as is shown at 222 and 204 for one trunk and at 223 and 205 for another trunk. Relays 224 and 225 are common to all the relays such as 204 and 205 that are associated with trunks to the same group of secondary line switches and control a chain circuit through these individual relays.

As hereinbefore described, on a call from station A to station B, the operation of the secondary line switch SLS-1 in a path including resistance 222 and relay 204 was stated to be dependent on the operation of relay 204. The resistance 222 is of such a value as will prevent the secondary line switch from plumping but will permit relay 204 to operate. The operation of relay 204 then closes a circuit for operating the secondary line switch; this circuit is traced from ground at the back contact of relay 224, conductor 242, back contact of relay 205, and back contacts of intermediate relays similar to relay 205, lower front contact and winding of relay 204, conductor 213, pull-down winding 202 and back contact of switch SLS-1, winding of line relay 201, over conductor 214, through back contacts of relays 207 and 210 of the master switch SMS, over conductor 215, through the back contact of relay 212, over conductor 216, and through the left winding of relay 211 to battery. When there fore, by way of example, two primary line switches in different groups of primary line switches connect simultaneously to line switches in the same secondary group as SLS-1 and SLS-25, relays 204 and 205 both operate. The operation of relay 205 closes a circuit from ground at the back contact of relay 224, over conductor 242, through the upper front contact and winding of relay 205, conductor 243, through the pull-down winding 252 of the secondary line switch SLS-25 and the winding of the associated line relay 251, over conductor 214, to battery through the left winding of relay 211 of the master switch SMS as hereinbefore traced. Since relay 205 is the first relay in the chain circuit from ground at the back contact of relay 224, the operation of relay 205 disconnects this ground from all of the succeeding relays in the chain so that relay 205 alone is effective to cause the energization of the pull-down winding of the associated line switch. The operation of relays 205 and 204 also completes a circuit for operating relay 224; this circuit is traced from battery through the winding of relay 224, lower front contact of relay 205, through the upper back contacts of intermediate relays similar to relay 205, through the upper front contact of relay 204, through resistance 222, over conductor 113, to ground at contact 121 of springs 138 of the primary line switch PLS-1. Relay 224 is slower in operating than the pull-down winding of a secondary line switch so that switch SLS-25 is at least partially operated before relay 224 opens its back contact; and the operation of line switch SLS-25 is then completed by the energization of both of its windings in series, this circuit being traced from battery through winding 253, the front contact and winding 252 of switch SLS-25 in series, conductor 243, winding of relay 205, resistance 223, conductor 229 to ground at the primary line switch by which this trunk was seized.

The operation of switch SLS-25 extends the connection from trunk conductors 226 and 227 over the trunk opposite whose terminal springs 45 the plunger of switch SLS-25 is at that time standing to a selector similar to D. The operation of switch SLS-25 also opens the circuit through its line relay 251 in the well known manner but the line relay being slow to release holds 50 operated for a short period and permits the ground that is returned from the selector over the conductor corresponding to conductor 219 to momentarily pass through front contact of relay 201 to conductor 243 and thereby shunt the winding of relay 205, causing relay 205 to release. When relay 205 releases as above described, relay 224 will release and close the chain circuit over conductor 242 thus preparing an operating circuit for the pull-down winding of secondary line 60 switch SLS-1. When the secondary master switch selects another idle trunk and reconnects battery over conductor 214, the switch SLS-1 operates to extend the trunk conductors 111 and 112 to an idle selector.

In the case of the two simultaneous calls just described, it was assumed that relay 224 does not remain operated long enough for the slow operate relay 225 to operate. When however during the busy period there is a scarcity of trunks to selectors and it is necessary for the master switch SMS to continue its search for an idle trunk, relay 224 70 may remain operated long enough to cause the operation of relay 225. In this case relay 225 restores ground to the chain circuit through the 75

individual relays 205 and 204. The time interval elapsing before relay 225 operates is sufficiently long to permit the master switch SMS to function and open the battery supply over conductor 214 at the back contact of relay 210. In this way the secondary line switch connected to the individual relay nearest the common relays 224 and 225 will be in a position to operate as soon as the master switch restores main battery to the secondary line switches.

What is claimed is:

1. In a telephone system, a group of lines, an electromagnetically operated plunger type line switch for each of said lines, a battery and a conductor for connecting said battery to the operating magnet of each of said switches, a bridge circuit comprising said conductor completed in response to the initiation of a call over any of said lines, said bridge being unbalanced when calls are initiated simultaneously over a plurality of said lines, and means responsive to said bridge being unbalanced for preventing the operation of any of said switches.

2. In a telephone system, a group of lines, an electromagnetically operated line switch for each line, circuits for operating the magnets of said switches, a first group relay the winding of which is included in each of said operating circuits, a shunt circuit closed by the operation of said first group relay, and a second group relay for preventing the simultaneous operation of more than one of said line switches, the winding of said second group relay being bridged across said shunt circuit and said operating circuits.

3. In a telephone system, a group of plunger type line switches each switch comprising a pull-down winding, a line relay for each switch, a first group relay, a second group relay, an operating path for the pull-down winding of each of said switches including a front contact of the associated line relay, the winding of said first group relay and normally closed contacts of said second group relay, a circuit in parallel with each of said operating circuits including normally open contacts of said first group relay, said second group relay being normally short-circuited by contacts of said first group relay, and means rendered effective by the operation of said second group relay for increasing the resistance in each of said operating circuits to prevent the complete operation of the associated line switches.

4. In a telephone system, a group of plunger type line switches, a relay individual to each of said switches, a relay common to said switches for preventing the simultaneous operation of more than one of the switches, circuits for operating the magnets of said switches, each operating circuit being controlled by the associated one of said individual relays and by said common relay, and a circuit closed only when a plurality of said individual relays are operated for operating said common relay.

5. In a telephone system, a group of plunger type line switches, a relay individual to each of said switches for operation upon seizure of the associated switch, a group of trunks connected to the terminal springs of each of said switches, a master switch for positioning the plungers of idle line switches in operative relation to an idle one of said trunks, means responsive to the operation of one of said idle line switches for causing the operation of said master switch to advance the plungers of the remaining idle switches to a position opposite another idle trunk, circuits for operating the magnets of said switches, each of said

operating circuits being controlled by the associated one of said individual relays, a control relay common to said switches for controlling all of said operating circuits, a circuit closed by the simultaneous operation of a plurality of said individual relays for operating said control relay to disable the operating circuits of all but one of said switches, and another relay operatively responsive to the operation of said control relay for rendering said operating circuits operatively effective while said control relay is operated, said other relay being slow in operating to allow the selection of another idle trunk by the operation of said master switch while said operating circuits are disabled.

6. In a telephone system, a plurality of lines, a line relay and a line switch for each line, operating circuits one for each of the line relays, operating magnets one for each of the line switches, a battery for use in operating said magnets, a first relay common to said switches, operating circuits one for each of said magnets, the operation of any one of said line relays being effective to close the operating circuit for the magnet of the associated line switch, said battery and the winding of said first group relay being included in each of the operating circuits of said magnets, a first resistance common to said line switches and approximately equal to the resistance of the operating winding of each of said magnets, a circuit including said battery and resistance closed by the operation of said first relay in response to the operation of any one of said line relays, a second relay common to said line switches, and a second resistance common to said line switches connected in series with said battery and said first relay and normally short-circuited by contacts of said second relay, the operation of only one of said line relays at a time being ineffective to cause the operation of said second relay and the operation of a plurality of said line relays at one time being effective to cause the operation of said second relay. 20 25 30 35 40 45 50 55 60 65 70

7. In a telephone system, a plurality of lines, a line relay and a line switch for each line, operating circuits one for each of the line relays, operating magnets one for each of the line switches, a battery for use in operating said magnets, a first relay common to said switches, operating circuits one for each of said magnets, the operation of any one of said line relays being effective to close the operating circuit for the magnet of the associated line switch, said battery and the winding of said first group relay being included in each of the operating circuits of said magnets, a first resistance common to said line switches and approximately equal to the resistance of the operating winding of each of said magnets, a circuit including said battery and resistance closed by the operation of said first relay in response to the operation of any one of said line relays, a second relay common to said line switches, and a second resistance common to said line switches connected in series with said battery and said first relay and normally short-circuited by contacts of said second relay, the winding of said second relay being normally short-circuited by contacts of said first relay, the operation of only one of said line relays at a time being ineffective to cause the operation of said second relay and the operation of a plurality of said line relays at one time being effective to cause the operation of said second relay and thereby prevent the operation of any of said magnets by opening the short circuit across said second resistance. 20 25 30 35 40 45 50 55 60 65 70
